UNITED STATES PATENT OFFICE

2,526,097

HOT-AIR DISCHARGING UNIT

Thorkell Sveinson, Winnipeg, Manitoba, Canada,
assignor to Selkirk Metal Products, Limited,
Winnipeg, Manitoba, Canada

Application April 4, 1947, Serial No. 739,463

1 Claim. (Cl. 98—46)

1

My invention relates to hot air discharging unit, an object of the invention being to provide means whereby over-heated air in the vicinity of a smoke pipe may be discharged through the adjacent ceiling and/or roof or through an adjacent wall.

A more specific object is to provide a hot air discharging unit assuming the form of a collar designed to encircle the portion of a hot air pipe which passes through a wall, or a ceiling and/or roof so that the hot air may either be conducted to the open air, or into a roof loft or attic.

Most particularly, the unit herein illustrated has for its objects the conduction past an insulated and vertically disposed portion of smoke pipe, over-heated air from the area in the vicinity of the smoke pipe elbow, through the ceiling and into the roof loft or attic where it assists in keeping the layer of insulation dry so reducing the possibility of spontaneous combustion and preventing discolouration of the ceiling around the smoke pipe.

A further object is to provide a device of the character herewithin described having an outwardly and downwardly, annularly bevelled and apertured upper shoulder over which material such as insulating particles will gravitate away from the hot smoke pipe rather than lie thereon with the possible danger of starting a fire.

With the above objects in view, and such other objects as may be implicit in the disclosure hereinafter, my invention consists of the following arrangement and construction of parts, reference being had to the accompanying drawing which illustrates the same in vertical cross-section and in combination with horizontally disposed and vertically disposed pieces of smoke pipe and a connecting elbow.

It is to be understood at the outset that the invention herein described and claimed is for use predominantly in association with a smoke pipe such as that illustrated, wherein the vertical portion 1 is provided with the spaced insulating jacket 2. The space between smoke pipe 1 and jacket 2 is designated by the numeral 3 and it will be seen that the smoke pipe 1 is held centred with respect to the jacket 2 by means of the cap 4 at the top, and the annular flange 5 at the bottom.

The aforesaid smoke pipe 1 is slideable endwise by virtue of its aforesaid relationship with the parts 5 and 6 by which it is to be understood the smoke pipe is only frictionally in contact, and it will be seen that the lower end 6 of my smoke pipe is in communication with the conventional

2

elbow 7 provided with cleanout cover 8, and via this elbow, with the horizontal smoke pipe 9.

The smoke pipe 1 and jacket 2 extend through ceiling 10 and roof 11, and in the plane (by which expression I mean between the upper and lower horizontal bounding planes) of the ceiling I encircle the smoke pipe 1 outside the jacket 2 with the multi-apertured hot air discharging unit collectively enumerated 11 which I will now describe.

10 The said unit comprises a collar 12, the upper and lower ends whereof are formed into the annular shoulders or flanges 13 and 14 each having a series of spaced apertures 15 and 16 therein.

As will be observed, the material of my collar 15 is predominantly in spaced relationship to smoke pipe 1, only the upper and lower annular perimeters 17 and 18 being in contact with the outer shell or lining 19 of jacket 2, and in the context it is to be understood I use the word "smoke pipe" 20 and "jacket" synonymously as in certain claims appended hereto with the explanation that in certain instances I might employ a unit such as herein described in association with an uninsulated smoke pipe.

25 The shoulder 13 is crimped between the apertures 15 while the shoulder 14 constructed to the configuration plainly illustrated in cross-section, is provided with the projecting flange portion 20 which provides a covering for the aperture made 30 in the ceiling to accommodate my pipe, jacket and collar.

From all the foregoing it will be recognised that I have provided a means whereby over-heated air may be discharged into an attic 21, and 35 it is to be understood that the air around or in the region of the uninsulated elbow 7 and the adjacent part of the horizontal smoke pipe 9, often becomes very hot due to the change in direction which the products of combustion have 40 to make at the aforesaid elbow. The overheating of these elbows transmitted to the surrounding air accordingly result very frequently in discolouration of the ceiling surface around the vertical portion of the smoke pipe, but such discolouration is entirely avoided by the aforesaid 45 structure.

Obviously, I may if desired, lengthen my collar 11 so that the same embraces the smoke pipe or the insulating jacket thereof throughout that 50 portion thereof which proceeds through the attic 21 and in this way excess heat may be carried out to the atmosphere. This, however, in most cases is unnecessary, since it is to be understood that the hot air carried off through the unit 55 as I have described it into the attic 21 is not

of a temperature likely to cause any damage therein.

Since many modifications can be made in the invention herein described and since the accompanying drawings have been prepared only to illustrate the relative arrangement and interaction of parts and not with regard to accuracy of dimensions for manufacturing purposes which in view of this disclosure I consider to entail merely mechanical skill together with the skill of the mechanical draftsman, and since many apparently widely different embodiments of this invention may be made within the scope of the accompanying claim without departing from the spirit and scope of the same it is intended that all matter contained in the accompanying specification shall be interpreted as illustrative only and not in a limiting sense and I desire only such limitations placed thereon as justice dictates.

What I claim as my invention is:

In combination with a smoke pipe when extending through a ceiling, a cylindrical collar spaced from and concentrically surrounding said pipe at its locus of intersection with said ceiling, said collar being of a length sufficient to extend from said ceiling to at least the horizontal plane occupied by the upper edges of the conventional ceiling joists, an upper, multi-apertured flange extending inwardly and upwardly from the upper edge of said collar to said smoke pipe, the inner

10
15

and outer perimetrical edges of said flange engaging the adjacent pipe and the upper edge of said collar respectively, and a lower, continuous, annular, multi-apertured flange secured to the lower edge of said collar, said lower flange extending downwardly and inwardly to said smoke pipe, the outer perimetrical edge of said lower flange extending beyond said collar and overlying the surrounding ceiling-hole-edge.

THORKELL SVEINSON.
